UNITED STATES PATENT OFFICE.

STANLEY W. PALMER, OF BEAVER DAM, WISCONSIN, ASSIGNOR TO SILAS MCCLURE,
OF BEAVER DAM, WISCONSIN.

ATTACHING DEVICE FOR STOVES.

1,413,992.

Specification of Letters Patent. Patented Apr. 25, 1922.

Application filed January 11, 1921. Serial No. 436,405.

To all whom it may concern:

Be it known that I, STANLEY W. PALMER, a citizen of the United States, residing at Beaver Dam, in the county of Dodge, State 5 of Wisconsin, have invented certain new and useful Improvements in Attaching Devices for Stoves; and I do hereby declare the following to be a full, clear, and exact description of the invention, such as will enable 10 others skilled in the art to which it appertains to make and use the same.

The object of the present invention is to provide improved means for detachably securing to the edge of a stove or range the 15 bar commonly used to serve as a protection to the user of the stove.

Such protecting bars are ordinarily removed during the shipment of the range, partly to economize in space, and partly to 20 avoid breakage. For this reason the brackets by which the rail is secured to the range top cannot be riveted to the top frame at the factory but must be put in place after the stove has been shipped to its destination. 25 When the brackets are made in one piece, as is usual, the holes in the top frame of the stove or range are counter-sunk to receive the boltheads, and it requires closer work than is usually applied in the art of stove- 30 making to have the bolthead flush with the top. In consequence, the bolt-heads either project above the top surface of the front frame or are sunken below the surface. As it requires two bolts to each bracket this 35 makes four unsightly places at the front edge of the stove top. Another fault with this manner of attachment is the tendency of the nuts to work loose and leave the brackets wobbly. The third fault is the 40 difficulty of threading each bolt into its nut, for the bolt is handled from above with a screw driver and the nut is underneath the frame where it cannot be seen and where its manipulation is difficult.

45 The improvement of the present invention resides particularly in making the rail-holding bracket in two parts, one part, in the form of a lug being riveted to the stove top frame (instead of being bolted). The 50 rivet ends are ground down and polished off while the frame is being finished and the top is thus made clean and free from bolt-heads. There is no danger that the lug will work loose. To this lug is bolted the other

part of the bracket. The face of the lug and 55 the face of the bracket are ribbed to fit one into the other, thus making a rigid connection, and the two parts are detachably secured together by a bolt which preferably is threaded directly into the stationary lug. 60

In the accompanying drawings, Fig. 1 is a perspective view of a part of a stove embodying the improved attaching device; Fig. 2 is an elevation partly in section of the attaching device secured to the stove top; 65 Fig. 3 is a view of the bottom of the attaching device shown in Fig. 2.

The stove, of which a fragment is illustrated in Fig. 1, has the usual top frame 10 offset at 11 to receive the lids or griddles 12. 70 At the front of the stove or range the frame 10 terminates as usual in a depending or downwardly extending flange 13.

A pair of lugs 14 are permanently secured to the under surface of top frame 10 and 75 just back of flange 13 by means of rivets 15. These lugs are put in place at the factory and the tops of the rivets are smoothed off and polished with the smoothing and polishing of the top so that neither the appearance nor the utility of the flat top surface of the stove is impaired and no projections or depressions appear along the edge of the top.

Each lug 14 forms one part of a two-part 85 bracket and has an inclined face 16 to which the other part 17 of the bracket is attached. Part 17 is recessed at 18 to overlap the lug and thus increase the rigidity of the joint, and the two parts are detachably secured 90 together by means of a bolt 19 preferably without a nut but threaded directly into the inclined portion of the lug 14.

Bracket 17 is sector-shaped and extends around the lower edge of flange 13 and terminates in a socket 20 at about the level of the top of frame 10. A bar 21 is held by sockets 20 in position along the edge of the stove or range to keep the clothing of the user out of contact with the hot and sometimes dirty top of the stove.

With the construction above described, there are no projecting bolt-heads or dirt-accumulating recesses along the stove top near its front edge, but, on the contrary, the 105 top has a smooth finished surface. The two-part brackets afford rigid support to the bar and do not permit the bar to work loose

during normal use of the stove. Furthermore, the bar can be quickly and easily detached from the range to lessen breakage in shipment, or to permit the range to be carried through a narrow doorway.

5 I claim:

1. The combination with a stove top and a protecting bar, of a two-part bracket, one part of which is permanently riveted to the 10 stove top behind the front flange, substantially as described.
2. The combination with a stove top and a protecting bar, of a two-part bracket for securing one end of said bar to said stove 15 top, said bracket being in two parts, one of which is permanently riveted to the stove top, and is detachably bolted to the other part to removably hold said rail in position.
3. The combination with a stove top and 20 a protecting bar, of a supporting bracket at each end of said bar, each of said brackets being in two parts fitted and bolted together to afford a rigid but detachable connection, one of said parts being permanently riveted

to the under-side of the stove top, substantially as described.

4. The combination with a stove top and a protecting bar, of brackets for attaching said bar to said top, each bracket being in two parts, one part of which is permanently riveted to the under-side of said top and has an inclined face, and the other part of which is recessed to engage said inclined face, and a bolt passing through one of said parts and threaded into the other to permit removal of said bar from said stove top when desired.

5. In stove and range construction, the combination with the top having a depending flange, and the protecting bar, of a two 40 part bracket for securing the bar to the top, the bracket comprising a part rigid with the bar and a part rigid with the top and arranged beneath the flange, and a releasable connection between the parts of each 45 bracket.

In testimony whereof I affix my signature.

STANLEY W. PALMER.
